FIG. 5

UNITED STATES PATENT OFFICE

ARTHUR DEAKIN, OF MONTREAL, QUEBEC, CANADA

CHAIN CONVEYER

Application filed September 21, 1927. Serial No. 221,015.

This invention relates to new and useful improvements in ovens wherein an endless carrier is provided and arranged to support the material to be baked upon its upper run, 5 and having horizontally disposed plates connected therewith to support the material.

The object of the invention is to provide simple and efficient plate supporting means which will be easily and quickly repaired 10 without dismantling the machine or stopping the operation of the machine for any length of time.

In the usual construction of conveyer, the material supporting plates are secured to the 15 links of a conveyer chain between which are mounted rollers of solid construction rotatably mounted on bushings surrounding pins passing through the links. The rollers are adapted to engage with a rail or guide. It 20 has been found that the main wear takes place on the bore of the rollers and that great difficulty has been encountered in replacing the solid rollers, as every outside link has to be removed thus weakening the construction 25 of the conveyer.

According to the present invention the above difficulty has been overcome by providing split rollers which are so constructed that the load is transmitted directly through the 30 rollers to the bushings. The rollers have means formed therein to position the sections of the rollers with respect to one another.

In the drawings which illustrate my invention:—

Figure 1 is a part sectional side elevation of the material conveyer for a bread oven.

Figure 2 is a fragmentary plan of the conveyer shown in Figure 1.

40 Figure 3 is a side elevation of the roller with the sections shown in dismantled relation.

Figure 4 is an end view of the roller.

45 Figure 5 is a side elevation of the roller shown in assembled relation.

Referring more particularly to the drawings, 11 designates carrier plates which are secured to the inner links 12 of a conveyer. Angles 13 are shown as the connecting medium for illustrative purposes. Connecting

the outer links 14 with the inner links 12 are the pins 15, and rotatably mounted thereon are the rollers 16. Bushings 17 are placed between the rollers and the pins. The rollers run on a suitable track 18 and engage with the teeth 19 of sprockets 20, which may be rotated by any suitable means. The material to be baked is mounted on the plates and is carried into the oven (not shown), the direction of movement of the conveyer being in the direction of the arrows 21. My improvement lies in the special construction of rollers, a detail of one of which is shown in Figures 3 to 5 inclusive. The rollers are formed in two sections 22 and 23. The bore is split centrally along the line 24, but section 22 has projections 25 which fit into cut-away portions 26 forming a step joint between the sections. Section 22 is provided with a recessed aperture 27 to receive the heads 28 of screws 29, the threaded portions of which engage with threaded apertures 30 formed in the section 23. The screws hold the sections together while the rollers are bored and turned on their faces 31. The same screws are used for holding the sections in position around the pins 15 and bushings surrounding same. Dowel pins 32 may also be provided to prevent shearing of the screws due to side thrust. These pins 32 fit into recesses 33 and 34 formed in adjacent faces of the sections of the roller.

It will be seen that when any undue wear takes place on the roller, the same may be removed by unscrewing the pins and pulling the sections apart and a new roller may be quickly and easily installed without interfering with the working of the machine to which the conveyer is attached. By stepping the roller joints, the weight is transmitted through the sections of the roller and is not taken up on the connecting screws or the dowel pins. The construction herein disclosed provides a simple means for making repairs to conveyers of this type which have been usually provided with solid rollers and the pins riveted to the links.

Having thus described my invention, what I claim is:—

1. A conveyer comprising a plurality of

links, plate supports secured thereto, pins passing through the adjacent ends of the links and split rollers rotatably mounted on the pins, said rollers having radially stepped joints arranged at opposite sides of and paralleling the bores of the rollers and means to hold the portions of the roller together.

2. A chain conveyer roller divided longitudinally to provide a pair of separable sections, each section being provided with a central longitudinally extending recess semicircular in cross section and adapted to register with the corresponding recess of the other section to form the complete bore of the roller
10 when the two sections are secured together, the meeting faces of the two sections extending at opposite sides of the bore being made substantially Z-shaped to provide a stepped joint between the sections and fastening devices for securing said sections together.
